UNITED STATES PATENT OFFICE.

ANSON O. KITTREDGE, OF SLATE HILL, AND FRANK M. LEAVITT, OF BROOKLYN, NEW YORK, ASSIGNEES TO THE VULCAN COMPANY, OF PENNSYLVANIA.

SHEET-METAL-SCROLL CUTTER.

SPECIFICATION forming part of Letters Patent No. 349,722, dated September 28, 1886.

Application filed October 29, 1885. Serial No. 181,311. (No model.)

To all whom it may concern:

Be it known that we, ANSON O. KITTREDGE and FRANK M. LEAVITT, citizens of the United States, residing, respectively, in Slate Hill and Brooklyn, counties of Orange and Kings, and State of New York, have invented certain new and useful Improvements in Sheet-Metal-Scroll Cutters, fully described and represented in the following specification and the accompanying drawings, forming a part of the same.

The object of this invention is to cut sheet metal into forms of irregular shape without first marking such shape thereon. This we effect by suitably connecting the sheet metal with an index which is passed over a stationary pattern, so as to move the sheet metal in the required path in contact with a vibrating cutter. In such a construction a narrow cutter is used, but requires to be automatically turned in the direction of the required cut; and our improvements therefore consist in means for moving the sheet metal in conformity with the path traced by an index upon a given pattern; in means for turning the cutting-edge simultaneously with the said index in the direction of the traced lines; in the means for withdrawing the cutter, while in motion, from the sheet metal, and in the means for varying the rate at which the sheet metal is moved against the cutter. In our construction the sheet metal is secured to a freely-movable table, to which an index is attached, and the movement of the index over a drawing or pattern outline serves to move the table and sheet metal in a path identical with that traced by the index. The operator is not required, with this construction, to move the weight of the table, although it is supported upon anti-friction rollers; but the table is propelled by the frictional contact of a roller pressed upon its surface in any direction in which the index may be turned, the roller being rotated by automatic mechanism, at a speed controlled by the operator, and the roller-support being turned by a rotary connection with the index, so that the table is fed in the direction of any curve or line to which the index may be conformed.

The invention also includes certain details of construction for varying and stopping the feed, all of which will be understood by reference to the annexed drawings, in which—

Figure 1 is a side elevation of a machine embodying these improvements, the parts being shown in section where hatched, and the support for the nearer end of the pattern-table being omitted from the drawing. Fig. 2 is a plan of the same. Fig. 3 is a side view, on an enlarged scale, of the devices for driving the feed-roller, the bed A' and the stand P being shown in section at their center line, as well as the gear m^3 , the ring P^4 , the end of the brace F' , and the three chain-wheels F^5 . Fig. 4 is a front view of the same devices, the parts hatched being shown in section on line xx in Fig. 3. Fig. 5 is a plan of the bracket in section on line ww in Fig. 3. Fig. 6 is a top view of the cross-head. Fig. 7 is a side view of the roll-carrier with the propellers and the feed-roller removed. Fig. 8 is a view of the under side of the arch, showing the lower end of the carrier, the ring attached thereto, and the anti-friction rolls which hold it in place. Fig. 9 is a section of the roll-carrier on line yy in Figs. 3 and 4. Fig. 10 is a plan of the front end of the arch, showing the mechanism for adjusting the vibrating cutter, one side of the spindle-bearing being broken away to show the swivel-collar beneath. Fig. 11 is a section of the same mechanism on line zz in Fig. 10, the cutter spindle and holder not being in section, the lower cutter and its holder being also displaced. Fig. 12 is a plan, and Fig. 13 an end, view of the holder for the lower cutter; and Fig. 14 is a front elevation of the machine.

The frame of the machine is shown formed in one piece of a bed, A, neck A', and arch A². B is a pattern-table affixed to the front end of the arch to sustain a drawing or pattern. C is an index carried at the lower end of a spindle, C', which is fitted to a goose-neck bracket, C². The foot of this bracket is secured to a feeding-table, D, from which project clamps O, to grasp the edges of the sheet metal, (shown at O' in Fig. 2.) The table is movable beneath the arch upon two sets of anti-friction wheels and tracks arranged at right angles to one another. Each set of wheels is fixed to a square frame formed of the axles D³ and tie-bars D⁴. The lower set of wheels, D², rest upon rails E, formed on the bed A, and carry a rectangular frame formed of two pairs of rails, E' and E²,

the former being fitted to the wheels D^2 , and the latter sustaining the upper wheels, D' , upon which rest rails E^3 , affixed to the table D .

Fig. 2 shows a pattern, B' , laid upon a table B , with the center of the spindle C' on a line with its left-hand end; and the spindle-bracket C^2 being rigidly affixed to the feeding-table, it is obvious that the movements of the latter must correspond in all respects with the movements of the index C over the pattern.

The feeding-table is propelled by a roller, G , pressed upon its surface and rotated automatically at the pleasure of the operator. The roller-carrier P' is mounted in the center 15 of the arch over the table to sustain the opposite ends of the roller-axle, and is attached to a vertical spindle, J' , which is connected by any suitable means with the index-spindle C' , so as to revolve once for each rotation of the latter. The front end of the arch is formed 20 with bearings a' , to which is fitted a vertical spindle, a , carrying a holder, a^2 , and the sheet-metal cutter d . Above the arch the spindle a is connected with a spindle, b , by means of cross-bars b' and pins b^2 , the pins being fixed in 25 one of the cross-bars and fitted loosely in holes in the other, so as to permit a reciprocating movement to the spindle a while it is rotated by the spindle b . The spindle b is held concentrically above the cutter-spindle by a standard, 30 H , and is, like the spindle J' , rotated by a connection to the index-spindle. The point of the index is concentric with its spindle, and it is formed with a sidewise projection or heel, c , to 35 guide the operator in applying the index to the pattern, and a hand-wheel, C^3 , is affixed to the index-spindle to turn the heel of the index into coincidence with the lines and curves of the pattern.

40 The rotary connection between the spindles of the index, the cutter, and the feed-roller G is formed by means of chains applied to wheels of equal diameters upon all the spindles, and a jointed connection is formed between the spindles C' and J' , to compensate for the various movements of the index over the pattern. For this purpose links F F' are jointed together by a pin, K , and their outer ends pivoted, respectively, upon the two spindles. 45 Two chain-wheels, F^2 , are affixed together to turn loosely upon the pin K , and three chain-wheels, F^3 , are attached to the top of the spindle J' . Wheels F^5 and F^4 are attached to the tops of the spindles b and C' , and the motion is communicated from one to the other by three chains, I , I' , and I^2 , connecting the different centers, as shown in Fig. 2. The third wheel upon the spindle J is employed to transmit a coincident rotary motion to a lower 50 shear-blade, e , against which the cutter d is arranged to operate. This cutter (shown in detail in Figs. 11 to 13) is mounted upon the top of a spindle, L , vertically concentric with the cutter-spindle, and sustained in bearings 55 L' , which project from the front of the bed A .

60 The cutters are shown herein as shear-blades, the lower one having a level surface, over

which the sheet metal is readily moved, and the upper one having an inclined edge, to lap upon the other, like other shears. Each blade 7c is clamped in a holder by a gib, e' , and bolt e^2 , and the lower holder is formed with a foot, f , fitted to a cross-piece, f' , upon the head of the spindle L . Slots f^2 are formed in the feet of this holder, as shown in Fig. 12, so that the 75 lower blade may be adjusted sidewise to secure a close contact with the face of the cutter d .

The spindle L is rotated by the intervention of a shaft, M , mounted upon the machine in the rear of the table, and provided with chain-wheels N and N' at its top and bottom. A chain-wheel, L^2 , is also applied to the lower end of the spindle L , and chains L^2 and N^2 serve to connect the shaft M respectively with the spindle J' and the spindle L . 85

As stated above, the movement of the index in following the lines of the pattern is effected by its connection with the feeding-table D , which is propelled by the roller G in any course in which the roller may be directed. It will therefore be understood that when the roller is in motion the feeding-table and the index move therewith, and the operator is required merely to turn the heel of the gage successively in the same direction, as the lines over which the gage is passing. Such turning is effected by the hand-wheel C^3 , and operates through the various chain-wheels and chains to turn the cutters and the feeding-roller simultaneously in the same direction, and to 90 cut in the sheet metal clamped to the feeding-table a line identical with the pattern. The cutter d operates by a vertical vibration, which is effected by a rapidly-revolving crank, n , connected to the cutter-spindle by a link, n' , a rocker, n^2 , and a collar, n^3 , fitted to a swivel, n^4 , screwed upon the spindle a . The rocker is interposed between the crank and spindle, so that the operator may separate the cutters to introduce the metal when desired, the rocker 95 being pivoted at its middle to a hanger, g , which is hung at its upper end upon an eccentric, g' , by which it is adjustable vertically while the cutter is in operation. The eccentric is fixed to a shaft, g^2 , which is rotated by 100 an arm, g^3 , and connecting-rod g^4 , actuated by a treadle, T . Shafts h and h' are fitted to the neck A' , to carry crank-arms for transmitting the motion of the treadle to the rod g^4 , and the rear end of the rod is fitted to a pin sliding in 105 a crank, i , to and from the center of the shaft h' , so as to receive a greater or less movement from its oscillations. A bell-crank, j , (hung on the shaft h ,) and a link, k , and arm l transmit the motion from the treadle to the shaft h' . 110

To shift the pin o to any point in the crank i it is connected by a link, o' , to an arm, o^2 , which is mounted upon a shaft, o^3 . A handle, o^4 , is connected by a rod, o^5 , to an arm, o^6 , upon the opposite end of said shaft, and operates, 115 when the handle is pushed inward, to draw the pin o toward the center of the crank i , and to diminish the motion transmitted to the eccentric g' . 120

A pin, k' , upon the bell-crank j serves to simultaneously draw downward a connecting-rod, which throws the feeding mechanism into operation, and the movement of the treadle thus serves to start the feed at the same time that the cutter is forced into the metal by the movement of the hanger g . The feeding mechanism consists in a friction-plate, r , and friction-disks s , which are mounted upon spindles s' , pressed toward the plate by springs s^2 . The spindles are mounted in bearings s^3 at opposite edges of the plate r , and are rotated in opposite directions by their pulleys s^4 , and the plate is mounted upon a shaft, r' , hung in bearings r^2 , and provided with a spring, r^3 , to hold it normally in the centers of the disks s , as it is represented in the drawings. To secure this effect the spring is applied to the shaft between two collars, with each of its ends abutting upon a loose washer, r^4 , placed inside the fixed collar. Braces r^5 are shown in section in Fig. 1, and in plan in Fig. 2, fixed upon the arch A^2 , and are formed with apertures which permit the passage of the collars, but resist the movement of either washer. It is obvious that a longitudinal motion of the shaft r' would move the plate from the center of the disks s , which would then operate to rotate the plate at a velocity corresponding with their point of contact. Such movement would press one of the collars and washers just described against the opposite washer, and thus compress the spring and induce the reaction required to restore the plate to its central position. Such end movement of the shaft is effected by a connection with the pin k' , which is actuated by the treadle, an arbor, l' , being mounted upon the neck A' over the said pin, and provided with an arm, l^2 , coupled to the shaft by a link, l^3 , and swivel l^4 . The descent of the treadle is intended to actuate the shaft r' in either direction, for which purpose the arbor l' is provided with a cross-bar, l^5 , having a pin, l^6 , at each end. A reversing - yoke, l^7 , provided with opposed hooks l^8 at its upper end, is linked to the pin k' , and a rod, l^9 , connects the yoke with a handle, l^{10} , adjacent to the pattern-table, so that the operator may throw one of the hooks into contact with either of the pins l^6 at pleasure. When hooked to the rear pin, as shown in Fig. 1, the depression of the treadle operates to draw the shaft r' backward, and to rotate the plate r in the direction of the arrow r^6 . When the yoke is hooked to the front pin, the depression of the treadle pushes the shaft r' forward, and produces a rotation of the plate r in the opposite direction. A brake-wheel, s^5 , having a convex rim, is secured to the shaft r' , and is clamped, when the plate r is in its neutral position, by two pressers, s^6 , affixed to the ends of levers s^7 . These levers are pivoted at the opposite side of the plate from the wheel s^5 , so as to cross the shafts s' , at which crossing the shafts are provided with collars s^8 , arranged to bear against projections s^9 on the levers. Such clamping action is intended to check the rotation of the plate r , so as to instantly stop the

feed when the plate is shifted to the center of the disks. The pressers s^6 are made round and pivoted upon the ends of the levers, and are automatically pressed toward the brake-wheel by the springs s^2 , operating through the collars s^9 . The inward movement of the spindles s is limited by the contact of the disks with the plate r , and the pressers are so proportioned that the brake-wheel, when the plate is moved to its neutral position, as shown in Fig. 2, operates to slightly separate them, thus pushing the levers s^7 apart against the resistance of the springs s^2 . Such a brake is required to overcome the momentum of the feeding-table and its driving apparatus when propelled in either direction by the rotation of the plate r , the shaft r' being connected with the feeding-roller through a combination of gearing. (Shown in Figs. 3 and 4.) In these views the roller-carrier P' and the supports of its spindle J' are shown upon a larger scale and partly in section.

P is a stand located upon the arch A^2 over the roller-carrier P' , and is provided at its upper end with a bearing, P^2 , for the spindle J' . The carrier is formed as an oblong hollow casting, (shown detached in Fig. 7,) the feed-roller being mounted upon an axle, p , in bearings p' in its lower end, and rotated by two vertically reciprocating propellers, m , which act upon two cranks, p^2 , attached to the end of the roller-axle. These cranks are set quartering, as shown in Figs. 3 and 4, and the propellers receive a suitable alternating motion from two crank-pins, m' , which are rotated in coincidence with the cranks p^2 . These crank-pins are fixed upon gear-wheels m^2 and m^3 , which are pivoted within the standard P , and are rotated by a pinion, m^4 , upon the shaft r' , which is extended through bearings m^5 , formed on the standard. The spindle J' is supported by the bearing P^2 vertically in front of the two gear-wheels, and is provided with two sliding cross-heads, m^6 and m^7 , each cross-head having a transverse groove, m^8 , to fit a block upon one of the crank-pins, and being guided vertically by slides P^8 . The spindle J' is formed on each side with a groove, as shown in Fig. 7, extending from its lower end to one of the cross-heads, and a sliding bar, t , is fitted to each groove and attached at its opposite ends to a cross-head and a propeller, as shown in Fig. 4. Each bar is attached to its propeller by a stud, t' , (shown in Figs. 4 and 9,) which projects through a slot, t^2 , in the carrier P' , and each bar is attached to its cross-head by a collar, t^3 , swiveled in the end of the cross-head by a bolted cap t^4 . The spindle J' is secured rigidly in the top of the carrier, as by pin J^2 , so as to turn the carrier when rotated by the chain-wheel F^3 , and the cross-heads slide up and down freely upon it when driven by the crank-pins m' , thus moving the bars t and the propellers m in whatever position the carrier may be turned. The cranks upon the carrier-roll and the crank-pins upon the gears being in both cases set at ninety degrees from one another, the propellers serve effectually to continuously rotate the feeding-roller when

the pinion m^4 is rotated by the friction feeding devices. As it has already been shown how these feeding devices are under the control of the treadle, so that the operator may at pleasure 5 rotate the plate r in either direction, or leave it normally at rest in the center of the disks s , it will be obvious that the direction and speed of the feeding-roller's rotations may be effectually governed while the cutters are operating upon 10 a sheet of metal. The feeding-roller is pressed toward the surface of the table D by a set-screw, u , applied to the top of the spindle J' ; but a yielding pressure may be employed by applying a spring or weight instead of a set-screw. 15 The carrier P' is provided at its lower end with a guide-ring, P^4 , secured thereto by bolts u' , and the ring is steadied by friction-rollers u^2 , bolted upon the bottom of the arch A^2 concentrically with the axis of the spindle J' , 20 as shown in Fig. 8. The sheet metal is not intended to lie upon the feeding-table, but to be held by its edges or corners, so as to move freely over the cutter e . The clamps O are therefore projected from the edge of the table, to 25 which they are movably secured by shoes O' and bolts v , fitted to a T-slot in the edge of the table. The clamps are hinged to the shoes at v' , and are each provided with a groove upon its upper surface, to which is fitted a movable dog 30 provided with a jaw, v^2 , and a clamping-screw, v^3 . One clamp projects from the table at each side of the cutters, so that the sheet metal may extend between them and beneath the cutter d , and by such dogs and by the hinging of the 35 clamps to the table a piece of sheet metal of any form may be grasped by any of its edges and participate in the movements imparted to the table by the feeding-roller.

The operation of cutting a bracket—such as 40 is shown upon the pattern-table—will be described, and will illustrate the action of the machine in cutting any other form. The pattern is rigidly secured to the table B, and to bring the index C over the end of the bracket 45 in the position shown in Fig. 2 it is necessary to actuate the feed without causing the cutters to penetrate the sheet metal. This is effected by pushing the handle o^4 and drawing the pin o to the center of the crank i , thus rotating the 50 eccentric g' and raising the collar n^3 and cutter d . The movement of the treadle then has no effect upon the eccentric, and the treadle may therefore be depressed to draw down the yoke l^2 and to move the plate r from the 55 center of the friction-disks in the required direction. The withdrawal of the wheel s^6 from the pressers s^6 permits the springs s^2 to force the disks against the plate r , and the gearing in the standard P and carrier P' 60 then operates to rotate the feeding-roller and propel the table. The heel of the index c being turned in the direction that it is desired to move the gage over the pattern, the roller immediately drives the table and the 65 gage in that direction, and when the gage has reached the edge of the pattern, as indicated in Fig. 2, the foot may be released from the

treadle, which is elevated by the action of the spring r^3 , and the feed is immediately stopped by the movement of the friction-plate to its 70 neutral position and the contact of the brake-wheel with the pressers s^6 . The clamps are then adjusted to hold the sheet metal, with one end adjacent to the cutters, in the same relation that the pattern bears to the index. The 75 operator then pulls the handle o^4 and forces the pin o outward in the crank i , thus rotating the eccentric g' and lowering the center of the rocker n^2 and the collar n^3 to force the cutters into contact, as shown in Fig. 11. The pulley 80 g^5 upon the crank-shaft g^2 is provided with a continuously-running belt, so as to vibrate the cutter d a constant amount, which is not varied or affected by the movement of such cutter toward the cutter e . The pattern shown upon 85 the table has straight parallel ends, and the cutters, when brought into action, therefore cut the metal on a line with one of such ends, and the heel of the index being turned toward the other end of such line the feed may be actuated to cut the line by depressing the treadle to rotate the plate r in the proper direction. When the point of the index has reached the end of such line, the feed would be stopped to 90 permit the operator to turn the index (by means of the hand-wheel C^3) at the proper angle to cut the next line of the pattern, and similarly, at any angle in the pattern, the feed may be arrested at the angle to properly adjust the index. When the feed is started to 95 cut a curve, the operator turns the index-spindle continuously, so as to conform the heel of the index to the varying direction of the curve, which may thus be completed without interruption. The position of the pin o in the crank 100 i determines the extent to which the eccentric g' is rotated and the cutter d moved downward, and the operator may therefore, when cutting curves, secure but a small lap of the cutters and sever the metal by a succession of very 105 short cuts, while a longer cut may be secured by forcing the cutter d farther down in cutting straight lines, so as to cut such lines more rapidly. It is obvious that when the pin o is at 110 the end of the arm the eccentric g' is affected by each movement of the treadle, and the cutter is then automatically withdrawn from the metal whenever the treadle is raised to stop the feed. The cutters are thus freed from the metal, so that they may be readily turned by the chain-wheel F^3 in the direction of a new line, as in 115 forming angles in the manner described above. The spring r^3 has been referred to as not only holding the plate r in a neutral position, but as operating to raise the treadle into the position shown in Fig. 1; but the treadle is in practice made with a counter-balance to raise it to such a position, although the same is not shown in the drawings, to avoid obscuring the other parts.

We have heretofore employed cranks in 120 place of the chain-wheels, with two links or connections to each from various points in the series, so as to effect the required rotary mo-

tion by rigid connections, but have exhibited chains herein as better adapted to illustrate the rotary motion desired.

From the above description it will be seen that one of the essential features of our invention is a construction for separating the cutters suddenly at the pleasure of the operator, while the machine is running, so as to stop the cut exactly at a given point or angle. To effect such separation it is obviously immaterial which of the cutters is retracted from the other, as the upper cutter may be vibrated in a constant position, and the opposed cutter lowered by the action of a treadle, when it is required to stop the cutting action.

Another essential feature of the invention is the means to avoid turning the sheet metal while feeding it toward the cutter, which is effected by the mounting of a vibrating cutter so as to be turned in the direction of different lines and curves upon the sheet metal. It is also obvious that with a cutter mounted to be thus turned in different positions, and to be opened to insert the sheet metal before commencing the cut, a great deal of scroll-work could be done without the use of any mechanism to hold or feed the sheet metal toward the cutters. We have not therefore limited ourselves to the entire combination of mechanism shown herein; but as we are the first to devise the improvements specified we claim the right to use a cutter adjustable in vertical planes, and to feed the sheet metal thereto by laying the same upon a stationary table and pushing it toward the cutting-edge by hand. In such case, however, the sheet metal would require to be plainly marked by scribing the needful lines thereon from a suitable profile-pattern, which would necessitate the possession or preparation of such a profile-pattern before the work could be commenced; but by the use of a suitable feeding mechanism as shown herein, and the connection of an index with the sheet of metal, as described, we are enabled to dispense entirely with profile-patterns fitted to transfer by scribing, and may use any drawing or sketch adapted to lie upon the pattern-table, and to guide the operator in controlling the movements of the index.

By the use of the automatic feed, which propels the feeding-table as long as the treadle is depressed, and at a rate of speed proportional to such depression, such control is effected by the mere turning of the index successively in the direction of the various lines of the pattern, the feeding movement being continued through the entire operation at rates of speed proportioned to the straightness of the lines cut, or interrupted at intervals, if necessary, to turn the feeding-roller and cutters at any abrupt corner or angle in the lines of the pattern.

It is obvious that our invention may be applied to the cutting of leather, pasteboard, and other substances, and we have not claimed herein a pair of cutters one of which is vi-

brated against the other, for two reasons: First, because such combination is not new, and, secondly, because it is not absolutely essential to the operation of our invention.

It is apparent that a narrow steel cutter not operating as a shears, but vibrated in contact with a flat surface of brass or rawhide, is adapted to cut a great many materials other than sheet metal. We do not therefore limit ourselves exclusively to the cutting of sheet metal with our appliances, as the means which we have described for feeding the material automatically to the cutter and for guiding it in conformity with a given pattern would operate the same, whatever the construction of the cutter may be or the material submitted to it.

We have not claimed herein the constructive features of this machine which adapt it for use without an automatic feed, but reserve the right to claim in a separate application, to be pending herewith, the combination of the vibrating cutter with an arched frame, the means for moving one cutter to and from the other by a treadle-connection extended beyond the arch A², the means for varying the throw of the cutter, and other constructive features shown, but not claimed, herein.

We are aware that a pair of shearing-blades have been mounted in opposition upon rotatable carriers, and that in such construction a hydraulic cylinder has been used to actuate the cutting-blade. In such construction, however, no mechanism has been applied to the separate tool-carriers to rotate them simultaneously when separated, as in our invention, nor has any mechanism been provided to simultaneously reciprocate and rotate the shearing-cutters while in operation, or while separated, as described herein. Our improvements, therefore, adapt a reciprocating cutter to be operated rapidly in the direction of the various lines and curves required in the manufacture of cornices and other sheet-metal work.

Having thus distinguished our invention from others, what we claim herein is—

1. The combination, with the opposed cutters of a sheet-metal-cutting machine, of means for reciprocating one of them and means for turning them simultaneously while reciprocating in the direction of different lines or curves upon the sheet metal, substantially as herein set forth.

2. In a sheet-metal-cutting machine, the combination, with a pair of cutters operating by shearing the sheet metal between them, of means for reciprocating one of the cutters, means for separating the cutters while reciprocating to introduce the sheet metal, and means for rotating the cutters simultaneously in relation to the sheet metal, substantially as shown and described.

3. In a sheet-metal-cutting machine, the combination, with a cutter and means for rotating it in relation to the sheet metal, of means

adapted to grasp the sheet metal and to feed it toward such rotatable cutter, substantially as herein set forth.

4. In a sheet-metal-cutting machine, the combination, with a cutter and means for rotating it in relation to the sheet metal, of means to grasp the sheet metal and move it toward the cutter and means for directing such movement in the line of the cutting-edge when the latter is turned in relation to the sheet metal, substantially as herein set forth.

5. In a sheet-metal-cutting machine, the combination, with a cutter, of a spindle adapted to turn the cutting-edge in relation to the sheet metal, an index mounted upon a spindle and provided with means for turning it by hand, and means for connecting the index and cutter spindles for rotating them simultaneously, substantially as herein set forth.

6. In a sheet-metal-cutting machine, the combination, with a cutter, of a movable table provided with means to grasp the sheet metal and hold it to the cutter and a support upon the table to carry a rotary index, an index mounted in said support, and means for rotating the index and cutter simultaneously, substantially as herein set forth.

7. In a sheet-metal-cutting machine, the combination, with a cutter, of a movable table provided with means to grasp the sheet metal and hold it to the cutter and a support upon the table to carry a rotary index, an index mounted in said support, the index having a concentric point and a heel or projection at one side of the same, for the purpose set forth, and means for rotating the index and the cutters simultaneously, substantially as herein set forth.

8. In a sheet-metal-cutting machine, the combination, with a cutter, of a movable table provided with means to grasp the sheet metal, a rotary index carried by said table, and a rotating feeding-roller pressed upon the surface of the table, and means for turning the index, the cutter, and the feeding-roller in the same direction relative to the sheet metal, substantially as herein set forth.

9. In a sheet-metal-cutting machine, the combination, with a cutter, of a movable table provided with means to grasp the sheet metal, a rotary index carried by said table, a rotating feeding-roller pressed upon the surface of the table, means for turning the index, the cutter, and the feeding-roller in the same direction, and means for varying the speed of the feeding-roller's rotations, substantially as herein set forth.

10. In a sheet-metal-cutting machine, the combination, with a cutter and means for turning it in relation to the sheet metal, of a movable table provided with means to grasp the sheet metal, a rotatable index carried by said table, a rotating feeding-roller pressed upon the surface of the table, means for turning the index, the cutter, and the feeding-roller in the

same direction, means for varying the speed of the feeding-roller's rotations, and means for reversing the direction of the roller's motion, substantially as herein set forth.

11. In a sheet-metal-cutting machine, the combination, with the freely-movable table D, of the feeding-roller G, adapted to move the table by frictional contact therewith, the carrier P', the shaft J', the cranks p², attached to the roller-axle, the propellers m, actuated by bars t, inserted in grooves in the shaft J', and cross-heads m⁶ and m⁷, fitted to the shaft and attached to the bars by collars t³ and actuated by crank-pins m', as and for the purpose set forth.

12. In a sheet-metal-cutting machine, the combination, with the movable table D, the feed-roller G, the carrier P', the shaft J', cross-heads m⁶ and m⁷, and means, substantially as described, for transmitting a crank motion from the cross-heads to the feeding-roller, of the gear-wheels m² and m³, provided with the crank-pins m', for actuating the cross-heads, and feeding mechanism adapted to rotate the said gears, and provided with means for varying the speed of such rotations and stopping the same at pleasure, substantially as herein set forth.

13. In a sheet-metal-cutting machine, the feeding mechanism for producing and controlling the rotations transmitted to the feeding-roller G, consisting in the revolving feeding-disks s, a friction-plate, r, mounted upon a shaft, r', with the brake wheel s⁵, a spring, r³, and braces r⁵, operating therewith to hold the plate r normally in the centers of the disks s, a treadle connected with means for moving the shaft r' longitudinally, and levers s', provided with pressers s⁶, and pressed toward the brake-wheel by springs, substantially as and for the purpose set forth.

14. In a sheet-metal-cutting machine, the combination, with a frame comprising a bed, A, neck A', and arch A², the tracks E upon the bed, a table, D, movable upon two sets of wheels, and intermediate rails, E' and E², as described, of the spindles a and L, carrying the cutters d and e, respectively, upon the arch A² and bed A, an index affixed to the table D, a pattern-table, B, supported beneath the index, means for vibrating one of the cutters, means for separating the cutters to introduce the sheet metal, and a feeding-roller arranged and operated by frictional contact with the table D, substantially as and for the purpose set forth.

In testimony whereof we have hereunto set our hands in the presence of two subscribing witnesses.
